No. 872,600.

PATENTED DEC. 3, 1907.

L. WHARTON.
SHIPPING CRATE.
APPLICATION FILED JUNE 16, 1906.

UNITED STATES PATENT OFFICE.

LEWIS WHARTON, OF CAMBRIDGE, OHIO

SHIPPING-CRATE.

No. 872,600.

Specification of Letters Patent.

Patented Dec. 3, 1907.

Application filed June 16, 1906. Serial No. 322,049.

To all whom it may concern:

Be it known that I, LEWIS WHARTON, a citizen of the United States, residing at Cambridge, in the county of Guernsey and State 5 of Ohio, have invented certain new and useful Improvements in Shipping - Crates, of which the following is a specification.

The present invention relates to crates of that character which are commonly employed for the shipment of eggs and similar articles, the object being to provide an improved device of this character which can be knocked down when returned to the shipper so as to occupy a comparatively small amount 10 of space and be handled at much reduced rates.

For a full description of the invention and the merits thereof and also to acquire a knowledge of the details of construction of 20 the means for effecting the result, reference is to be had to the following description and accompanying drawings, in which:

Figure 1 is a perspective view of the crate when distended: Fig. 2 is a similar view 25 taken from the opposite side of the crate and showing the same as partially folded. Fig. 3 is a perspective view of the crate when completely folded.

Corresponding and like parts are referred 30 to in the following description and indicated in all the views of the drawings by the same reference characters.

The numeral 1 designates the bottom of the crate, which, in the present instance, is 35 rectangular in shape and is provided along one of its longitudinal edges with the upwardly projecting strip 2. The two sides 3 and 3' of the crate are hinged, respectively, to the upper portion of the strip 2 and to the 40 edge of the bottom 1 opposite the strip 2. When the crate is folded, the side 3' folds over upon the bottom and the side 3 folds over upon the side 3', the strip 2 extending upwardly above the bottom for a distance 45 equal to the width of the side 3' and the latter mentioned side having a height corresponding to the width of the bottom 1. The ends 4 and 4' of the crate are each formed in two sections, the lower sections 5 and 5' being 50 rigidly secured to the ends of the bottom 1, while the upper sections 6 and 6' are hinged to the lower sections.

It will be observed that the lower section 5 has a height corresponding to the combined 55 thickness of the two sides of the crate and is somewhat smaller than the lower section 5'

which has a height corresponding to the combined thickness of the two sides and the opposite end 4.

In order to hold the ends and sides rigidly 60 in position when the crate is distended, the upper sections 6 and 6' of the ends are provided with the headed studs and the sides are provided with the hooks 8 which fit around the shanks of the studs 7 and engage with 65 the heads thereof to prevent the members from folding either inwardly or outwardly. The cover to the crate is formed in the two transverse sections 9 and 9' which are hinged, respectively, to the upper sections 6 and 6' of 70 the ends 4. The hinges 10 by means of which this connection is brought about are, preferably, secured to the inner faces of the members so that the adjacent edges thereof 75 will form stops to limit the swinging movement.

In folding the crate, the members 9 and 9' of the cover are swung upwardly so as to practically form continuations of the ends 4 and the same are then folded inwardly upon 80 the sides 3, the upper section 6' of the end 4' and the section 9' of the cover fitting against the upper section 6 of the end 4, and the section 9 of the cover.

In the preferred construction, the combined length of the upper section 6 of the end 4 and the section 9 of the cover is approximately equal to the length of the bottom 1 and a very compact structure thus obtained when the crate is folded. Hook members 11 85 are located upon opposite sides of the bottom 1 and engage with the headed studs 7 upon the ends of the crate to hold the various parts of the latter closely into contact with each other when folded. A hook 12 is also 90 provided for locking the two sections 9 and 9' of the cover together when the crate is 95 distended.

If desired, a transverse partition 13 may be employed and in the present instance is 100 shown as fitting loosely in grooves 14 in the sides of the crate.

Having thus described the invention, what is claimed as new is:

1. In a device of the character described, the combination of a bottom, a side designed to be folded against the bottom, a second side folding against the first mentioned side, ends carried by the bottom and designed to fold against the before mentioned sides, 105 studs projecting from the ends, hooks secured to the sides and designed to engage the 110

studs to hold the sides and ends rigidly in position when the crate is distended, and a second set of hooks secured to the bottom and adapted to engage the studs to hold the 5 sides and ends closely against the bottom when the crate is folded.

2. In a device of the character described, the combination of a bottom, a side designed to be folded against the bottom, a second 10 side folding against the first mentioned side, ends, a cover section hinged to each end, one of the ends and the cover section hinged thereto folding against the last mentioned side, while the opposite end and correspond- 15 ing cover section folds against the first men-

tioned end and cover section, studs projecting from the ends, hooks secured to the sides and designed to engage the studs to hold the members rigidly in position when the crate is distended, and hooks secured to the bottom and adapted to engage the before mentioned studs to hold the members closely together when the crate is folded. 20

In testimony whereof I affix my signature in presence of two witnesses.

LEWIS WHARTON. [L. S.]

Witnesses:

C. B. HUTCHISON,

A. J. LINGENFELTER.
